Primary Examiner — Paula Greene(74) *Attorney, Agent, or Firm* — NSIP Law**CLAIM**

I claim the ornamental design for a speaker for home theater, as shown and described.

DESCRIPTION

FIG. 1 is a front perspective view of a speaker for home theater showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another front perspective view, in which a television receiver in dot-dash broken lines is provided to illustrate an example environment.

The broken lines in the figures show portions of the speaker for home theater which form no part of the claimed design. The dot-dash broken line showing of the television receiver in FIG. 8 is for the purpose of illustrating environmental structure and forms no part of the claimed design.
